UNITED STATES PATENT OFFICE.

JOSEPH O. CLARK, OF BOSTON, MASSACHUSETTS, ASSIGNOR TO THE PHOENIX MANUFACTURING COMPANY, OF SOUTH BERWICK, MAINE.

CURTAIN-ROD FIXTURE.

SPECIFICATION forming part of Letters Patent No. 633,569, dated September 26, 1899.

Application filed May 19, 1899. Serial No. 717,420. (No model.)

To all whom it may concern:

Be it known that I, JOSEPH O. CLARK, a citizen of the United States, residing at Boston, in the county of Suffolk and State of Massachusetts, have invented certain new and useful Improvements in Curtain-Rod Fixtures, of which the following is a specification, reference being had therein to the accompanying drawings.

10 Figure 1 shows a curtain-pole held in place by my new fixture. Fig. 2 shows an end view of my new fixture. Fig. 3 is a sectional view on line 3 3, Fig. 2.

15 The object of my invention is to provide a fixture for poles for curtains, portières, and the like which is cheap in manufacture, simple in construction, and efficient in use and which will admit of the ready adjustment of the pole.

20 My invention does away with the need of all brackets, and thereby obviates the defacing of the window and door frames by screws, nails, and the like.

25 In the drawings illustrating the principle of my invention and the best mode now known to me of applying that principle, *a* is the curtain-pole, over the ends of which is passed a thimble *b*. The thimble *b* is divided into an outer and an inner portion by the partition-disk *c*, forming a recess at the end thereof. Sliding telescopically in the outer portion of the thimble *b* is the cap *d*, the end face of which is provided with a non-slipping material, as corrugated rubber. A spring *e* rests upon the disk *c* and presses the cap *d* firmly against the wall. A pin *f*, secured to the cap *d*, passes through the disk and centers the cap *d*.

My new fixture requires no brackets and permits the ready fitting and adjustment of the curtain-pole. It obviates the use of screws, 40 nails, and the like, and so obviates the defacing of the walls. The providing of the cap with rubber or other non-slipping material on its end or abutting face is a feature of my invention. 45

What I claim is—

1. The combination with the end of a curtain-pole or the like, of a thimble fitted on the end of the pole and having a recess at the end thereof; a telescopic cap mounted in said recess; a coiled spring mounted in said recess between the end of the pole and the end wall of the cap; and non-slipping material secured exteriorly on the outer end of the cap. 50

2. As a new article of manufacture, the curtain or like rod fixture herein described, the same comprising a thimble divided between its ends into two compartments by a transverse partition-disk; a telescopic cap mounted in one of said compartments; non-slipping 55 material secured on the outer end of the cap; a coiled spring mounted between the cap end and the transverse partition of the thimble; and a pin secured to the cap and passing through said partition-disk. 60

65 In testimony whereof I affix my signature in presence of two witnesses.

JOSEPH O. CLARK.

Witnesses:

EDWARD S. BEACH,
E. A. ALLEN.
